UNITED STATES PATENT OFFICE

2,373,792

TUYÈRE BLOCK

Earl A. Strang, Waukegan, Ill.

Application February 19, 1943, Serial No. 476,478

1 Claim. (Cl. 110—44)

This invention relates to a tuyère block for a coal stoker.

Among the objects of my invention is to provide a coal stoker having a shroud and aeration members for associating the shroud with the fire pit so as to direct air currents to the top layers of the coal in the fire pit for better burning and economy and such other objects, advantages and capabilities as will later more fully appear and which are inherently possessed by my invention.

While I have shown in the accompanying drawing a preferred form of my invention, yet I wish it understood that the same is susceptible of modification and change without departing from the spirit of my invention.

Referring to the drawing, Figure 1 is a sectional view of the fire pit, shroud and tuyère blocks; Figure 2 is an enlarged front elevated view and Figure 3 a perspective view of one of my tuyère blocks.

The embodiment selected to illustrate my invention comprises a burning pit or retort 10, receiving one end of a hollow pipe or tube 11.

A shroud 64 surrounds fire pit 10. A plurality of cast iron blocks 65 serve the double function of attaching the shroud to the fire pit and providing air channels for aerating the top portion of the coal in the fire pit.

Each of the blocks 65 has a top portion 66, a downwardly extending rear wall 67 curved outwardly and upwardly at its bottom to form a

hook 68, an abbreviated front wall 69, oppositely disposed side walls 70 each having a portion cut inwardly through the front wall 69 to a point forwardly from the rear wall 67 and constituting spaced recesses 71. A transverse groove 72 is cut between side walls 70. The blocks are placed contacting each other and with grooves 72 engaging the top edge 73 of fire pit 10 and hooks 68 engage the curved lip 74 of shroud 64.

Air comes up from the bottom of shroud 64 and passes up through channels 71 to the top layers of the coal in fire pit 10.

Having thus described my invention, I claim:

In a stoker having a fire pit adapted to hold coal and a surrounding shroud having a curved lip, a plurality of aeration blocks, each of said blocks having a top portion, a downwardly extending rear wall curving outwardly and upwardly at its bottom portion to form a hook, an abbreviated front wall, oppositely disposed side walls each having a portion cut inwardly through the front wall to a point forwardly from the rear wall and constituting spaced recesses and a transverse groove cut between the side walls, said blocks positioned with said grooves engaging the top edge of the fire pit, and said hooks engaging the curved lip of the shroud, so that air coming up from the bottom of the shroud passes through the recesses to the top layers of coal in the fire pit.

EARL A. STRANG.
